UNITED STATES PATENT OFFICE.

JOHN ZILLIOX, OF ORCHARD PARK, NEW YORK.

LUGGAGE CARRIER.

Application filed December 21, 1921. Serial No. 523,981.

To all whom it may concern:

Be it known that I, JOHN ZILLIOX, a citizen of the United States, residing in Orchard Park, in the county of Erie and State 5 of New York, have invented new and useful Improvements in Luggage Carriers, of which the following is a specification.

This invention relates to a luggage carrier which is more particularly designed 10 for use on the running boards of automobiles and similar places so that luggage or baggage may be conveniently carried upon the same.

It is the object of this invention to provide 15 a luggage carrier which can be compactly folded and stowed away when not in use, but which when assembled and mounted on the running board of a car will provide a rigid, strong and reliable support for the 20 baggage which is to be carried, and yet is simple and comparatively inexpensive in construction.

In the accompanying drawings:

Figure 1 is a perspective view of my improved luggage carrier assembled ready for use. Figure 2 is a perspective view of the several parts of this luggage carrier dismembered and folded compactly ready for storage. Figure 3 is a fragmentary vertical 30 section, on an enlarged scale, taken on line 3-3, Fig. 1 and showing the brace locked in its operative position on the base. Figure 4 is a similar view, but showing the brace unlocked and partly disconnected. Figure 5 is a fragmentary vertical section taken on line 35 5-5, Fig. 1, showing the brace in its operative unfolded position relative to the adjacent standard. Figure 6 is a similar view, but showing the brace and standard folded 40 relatively to each other. Figure 7 is a fragmentary vertical section taken on line 7-7, Fig. 1 and showing the lower end of one of the standards coupled with the base ready for use. Figure 8 is a similar view of the 45 standard and base separated from each other preparatory to stowing away the luggage carrier when the same is not required for use.

Similar characters of reference refer to 50 like parts throughout the several views.

In its general organization this luggage carrier comprises a plurality of bases which are preferably constructed in the form of clamps and adapted to be detachably secured 55 to the running board of a car, standards rising from these bases and detachably

connected therewith, braces each of which detachably connects the upper end of one of the standards with the inner end of one of the bases, and a foldable wall which connects the two standards and which permits of lengthening or shortening the luggage carrier as a whole to the particular place where the same is to be used. 60

Each of the supporting bases in its preferred form preferably comprises an upper jaw or arm 10 which is adapted to be arranged transversely on the upper side of the running board of a car, a lower jaw or arm 11 adapted to be arranged transversely underneath the running board, an upright web 12 connected with the outer ends of the jaws 10 and 11 and a vertical clamping screw 13 arranged in a threaded opening at the inner end of the lower jaw 11. 70

This base is moved inwardly upon the running board of a car until its web 12 engages with the outer edge thereof and then the clamping screw 13 is tightened so as to draw the upper jaw 10 against the upper 80 side of the running board while the screw 13 bears against the underside of the same. 75

Each of the standards is preferably constructed in the form of an upright bar 14 of metal and has its lower end detachably connected with the outer end of the base, this being preferably accomplished by providing the outer side of the web 12 of the base with a button having a contracted neck 15 and an enlarged head 16 at the outer end of 90 the neck and providing the lower end of the respective standard with a longitudinal slot 17 extending to the lower end thereof. 85

For the purpose of attaching this standard to the respective base the standard is 95 pushed with its lower forked end downwardly astride the neck 15 of the button until the upper end of the slot 17 therein bears against the upper side of the neck and the lower part of this standard is confined between the head 16 of this button and the adjacent surface of the web 12, as shown in Fig. 7. These parts may be readily disengaged by lifting the standard from the button on the web 12, as shown in Fig. 8. 100

Each of the braces 18 is also preferably constructed in the form of a flat metal bar and when in use the same is arranged in an inclined position and extends from the upper end of one of the standards on the inner 110 side thereof to the upper side of the upper clamp or base arm 10 at the inner end there-

of. This brace is detachably connected at its lower end with the inner end of the base arm 10 by means which are preferably constructed as follows:

5 19 represents the neck of a button projecting upwardly from the inner part of the base arm 10 and 20 the enlarged head at the upper end of this neck. At the lower end of the brace 18 the same is provided with 10 a laterally projecting toe 21 and at the angle between the body of this brace and its toe is formed a key hole slot, the narrow portion 22 of which is formed in the toe 21, while the enlarged part 23 thereof is formed 15 in the lower end of the adjacent body portion of the brace 18. For the purpose of coupling this brace with the base arm 10 the toe is placed upon the base arm 10 in such a position that the head 20 of the respective 20 coupling button is arranged within the enlarged portion 23 of the key hole slot in the respective brace, as shown in Fig. 4. Upon now moving the lower end of the brace outwardly, the narrow part 22 of this 25 key hole slot will be engaged with the neck 19 of this coupling button and the head 20 of the latter will overhang the upper side of the toe 21, as shown in Fig. 3 and at the right hand side of Fig. 1, thereby holding 30 the brace 18 and the upper base arm 10 against vertical displacement relatively to each other.

This brace is locked in this position while the luggage carrier is in use by means of a 35 detent or latch 24 which is pivoted by means of a rivet 25 or otherwise, to the outer lower part of the respective brace and swung downwardly so as to be interposed between the brace 18 and the button head 20, as 40 shown in Fig. 3 and at the right hand side of Fig. 1. As long as the parts are in this position, each of the braces will be securely coupled with the upper part of its face and when it is desired to detach this brace from 45 its base preparatory to knocking down the luggage carrier and stowing the same away, this can be readily done by first swinging this detent from its lower interlocking position shown in Fig. 3 to its upper inoperative 50 position out of engagement from the button head 23, as shown in Fig. 4, after which the coupling button 19, 20 may be withdrawn from the key hole slot 22, 23 and the parts dismembered ready for packing.

55 The upper end of each brace 18 is pivotally connected with the upper end of one of the standards 14 by means which will permit these parts to swing freely relatively to each other for folding or unfolding the 60 same, but still permanently connecting them and forming a joint therebetween which will render the luggage carrier rigid while in use. In its preferred form this pivotal connection is constructed as follows:

65 On the upper inner side of each standard

is mounted a button which projects inwardly therefrom and which has a reduced neck 26 connected with the standard and an enlarged head 27 at the inner end of this neck. At the upper end of the brace 18 the same is 70 provided with an inwardly offset lip 28 which is curved in the direction of the length of the brace and engages its convex outer side with the upright flat inner side of the respective standard 14 and is also provided 75 with a longitudinal slot 29 which receives the neck 26 of the adjacent coupling button while the head 27 of this button engages with the inner side of the lip 28. In the operative position of the brace 18 the lip 28 is drawn downwardly until the upper end of the slot 29 engages with the neck 26 of this button and the brace is turned so that its body is arranged at an angle and extends from the upper end of the standard 14 to the inner end of the base bar or jaw 10. When folding the luggage carrier the brace 18 is swung outwardly toward the inner side of the standard 14 so that the same is 80 parallel therewith and also moves slightly upwardly during which time the convex face of the lip 28 slides on the inner side of the standard and this brace is shifted so that the inner end of the slot 29 of this lip engages with the underside of the button neck 95 90 95 26, as shown in Fig. 6.

The wall of the luggage carrier is preferably constructed so as to be capable of expansion and contraction lengthwise of the running board of the car to suit the length of the same or adapt it to other conditions. For this purpose, the side wall is preferably constructed of two pairs of folding bars which are connected with each other and with the standards 14. In the preferred 100 construction the bars 30 and 31 of each pair cross each other and are pivotally connected at the crossing by means of a rivet 32 or other suitable means and the bar 30 has its lower outer end pivotally connected by means 105 of a rivet 33 with the lower part of one of the standards while its upper end is pivotally connected by means of a rivet 34 or otherwise with the upper end of the wall bar 30 of the other pair. The folding bar 31 of each pair is pivotally connected at its inner end by a rivet 35 or otherwise, with the inner end of the bar 31 of the other pair, and its outer end is slidably connected with the 110 upper part of one of the standards, this being 115 preferably accomplished by a rivet 35 arranged on the upper outer end of the bar 31 and moving in a vertical slot 36 in the upper part of the respective standard, as 120 shown in Figs. 1, 2, 5 and 6.

When the luggage carrier is in use and the two standards 14 are spread apart the wall bars 30, 31 are unfolded and the upper ends of the bars 31 slide downwardly on the upper ends of the standards until the rivets 130

35 reach the lower ends of the slots 36, as shown in Figs. 1 and 5. Upon moving the two standards 14, 14 toward each other preparatory to folding the luggage carrier and 5 storing the same, the two pairs of wall bars 30, 31 are folded relatively to each other and the outer ends of the bars 31 slide outwardly on the bars 14 until the guide rivets 35 thereof engage the outer ends of the slots 36 in 10 the standards, as shown in Fig. 6.

In the dismembered and contracted position of the several parts of the luggage carrier ready for stowing the same away, the two standards are moved toward each other 15 to their fullest extent so as to fold the side wall, the lower ends of the standards are detached from the outer ends of the clamping bases and the braces are detached at their lower ends from the guiding faces and 20 moved inwardly toward the standards in which condition these parts may be arranged close together, as shown in Fig. 2, for stowing away in a comparatively small space when not required for use.

25 When, however, these parts are assembled and mounted on the running board of a car ready for use, the same forms a very rigid and durable structure which will effectively carry the load which may be placed within 30 the same.

This luggage carrier is comparatively simple in construction, the same has no delicate parts which are liable to get out of order, and the same can be readily put up 35 or knocked down without the use of any special tools for this purpose.

I claim as my invention:

1. A luggage carrier comprising a horizontal base, a standard connected at its 40 lower end with one end of said base and provided at its upper end with a button having a reduced neck and an enlarged head, and a brace detachably connected at its lower end with the opposite end of said base 45 and provided at its upper end with a curved lip which engages its convex side with said standard and which has a longitudinal slot receiving the neck of said button.

2. A luggage carrier comprising a hori-

zontal base, provided at one of its ends 50 with an upwardly projecting button having a reduced neck and an enlarged head, and a brace having an inclined body pivotally connected at its upper end with the upper end of said standard and provided at its lower end 55 with a horizontal toe adapted to rest on the opposite end of said base and having a key-hole slot the narrow part of which is arranged lengthwise in said toe and adapted to receive said neck and the enlarged part 60 of which is arranged in said body adjacent to its toe and is adapted to form a passage for said head.

3. A luggage carrier comprising a horizontal base provided at one of its ends with 65 an upwardly projecting button having a reduced neck and an enlarged head, a brace having an inclined body pivotally connected at its upper end with the upper end of said standard and provided at its lower end with 70 a horizontal toe adapted to rest on the opposite end of said base and having a key-hole slot the narrow outer part of which is arranged lengthwise in said toe and is adapted to receive the neck of said button 75 and the wide part of which is adapted to form a passage for said head, and a detent arranged on said body and adapted to engage with the inner side of said head.

4. A luggage carrier comprising a horizontal base provided at one of its ends with 80 an upwardly projecting button having a reduced neck and an enlarged head, a brace having an inclined body pivotally connected at its upper end with the upper end of said standard and provided at its lower end with 85 a horizontal toe adapted to rest on the opposite end of said base and having a key-hole slot the narrow outer part of which is arranged lengthwise in said toe and is 90 adapted to receive the neck of said button and the wide part of which is adapted to form a passage for said head, and a detent pivoted on said body and adapted to fit between the inner side of said head and the 95 adjacent side of the body of the brace.

JOHN ZILLIOX.
